UNITED STATES PATENT OFFICE

2,424,239

MACHINE FOR LASTING WELT-TYPE SHOES

Jacob S. Kamborian, West Newton, Mass.

Application January 15, 1944, Serial No. 518,321

34 Claims. (Cl. 12—2)

1

This invention pertains to a machine of the kind which includes means for imparting stress to flexible material and for making and inserting fasteners, for instance staples, into the stressed material, in its more specific embodiment to a shoe lasting machine, and relates more particularly to a lasting machine having novel means for forming and driving wire staples.

The patent to Kamborian No. 2,251,285, dated August 5, 1941, discloses a lasting machine which employs a highly desirable type of upper stressing and in-wiping mechanism together with means for applying adhesive for uniting the inlasted margin to the under surface of the insole, or alternatively to insert staples through the margin and substantially perpendicularly into the inner sole.

In its more specific aspects the present invention constitutes an improvement upon the machine of the aforesaid patent. One object of the present invention is to provide a machine of the general type of that shown in said patent but capable of lasting welt-type shoes and comprising means for applying lasting and in-wiping stress and for inserting staples to secure the lasted-in margin directly to the insole rib. A further object is to provide a machine including means for applying lasting stress progressively and without intermission, if desired, along the entire periphery of the last bottom and of inserting individual fasteners through the lasted-in margin of the upper and into a sole member, the fasteners being advanced, during insertion, in a direction substantially parallel to the under surface of the sole member. A further object is to provide improved staple-forming and driving means whereby staples may be inserted (without danger of distortion or breaking) into hard and dense material. A further object is to provide staple-forming and inserting means in combination with upper stressing and in-wiping means together with mechanism operative to actuate said several instrumentalities in properly timed relation with respect to a shoe presented to the machine by the operator. A further object of the invention is to provide a lasting and staple-inserting mechanism of simple, durable and reliable type capable of lasting shoes with great rapidity.

Other and further objects and advantages of the invention will be pointed out hereinafter in the following more detailed description and by reference to the accompanying drawings where-in

Fig. 1 is a fragmentary elevation of the left-

2

hand side of a machine embodying the present invention;

Fig. 2 is a fragmentary elevation, partly in vertical section, of the right-hand side of the machine;

Fig. 3 is a vertical, front-to-rear section, showing the driving connections for the lasting rolls;

Fig. 4 is a fragmentary elevation to larger scale than the Fig. 3, with certain parts in vertical section to illustrate the means for actuating the staple-forming and driving instrumentalities;

Fig. 5 is a fragmentary plan view of the machine with certain parts broken away;

Fig. 6 is a fragmentary horizontal section substantially on the line 6—6 of Fig. 4;

Fig. 7 is a front elevation, with the drive shaft broken off, showing the staple-forming and driving means removed from the machine;

Fig. 8 is a horizontal section substantially on the line 8—8 of Fig. 7;

Fig. 9 is a plan view of the staple-forming and driving mechanism of Fig. 7;

Fig. 10 is a perspective view, partly broken away, showing certain elements of the staple-forming and driving mechanism together with an eccentric for actuating one of said parts;

Fig. 11 is a fragmentary perspective view to larger scale than Fig. 10 showing certain parts of the staple-forming and driving mechanism, in particular the means for forming the staples;

Fig. 12 is a fragmentary perspective view showing a portion of the staple-driving mechanism, including the means for holding the formed staple, and the driver;

Fig. 13 is a section to large scale substantially on the line 13—13 of Fig. 8;

Fig. 14 is a fragmentary plan view partly in horizontal section and to large scale showing the wire-cutting element as it advances toward the cutting position;

Fig. 15 is a similar view showing the cutting operation as having been completed and the forming anvil in position to initiate the forming of the staple;

Fig. 16 is a view showing the cutting and forming head as advanced to its maximum forward position, showing the formed staple within the head;

Fig. 17 is a section on the line 17—17 of Fig. 16;

Fig. 18 is a plan view showing the staple within the forming head and with the driver in engagement with the closed end of the staple in readiness to insert it into the work;

Fig. 19 is a section, to larger scale, on the line 19—19 of Fig. 18;

Fig. 20 is a section, to larger scale, on the line 20—20 of Fig. 18;

Fig. 21 is a section to larger scale on the line 21—21 of Fig. 16;

Fig. 22 is a fragmentary longitudinal section with parts positioned as in Fig. 16, showing the anvil in position within the forming head at the completion of the forming operation;

Fig. 23 is a view generally similar to Fig. 22 but showing the anvil elevated in readiness for the advance of the driver;

Fig. 24 is a side elevation of the means for advancing the wire toward the cutting and forming point;

Fig. 25 is a section on the line 25—25 of Fig. 24;

Fig. 26 is a fragmentary vertical section in the plane of the axes of the lasting rolls showing the shoe in the position for lasting and with the wiper in its most advanced position;

Fig. 27 is a fragmentary front-to-rear vertical section through the staple-forming block; and

Fig. 28 is a fragmentary side elevation of the staple driver.

Referring to the drawings the numeral 1 designates a hollow, cast-metal standard designed to be mounted upon a suitable support for instance a bench. Resting on the top of this hollow standard is a base plate 2 (Fig. 3) on which is mounted the frame 3 which supports most of the operative instrumentalities and which provides bearings at 5 and 6 for the substantially horizontal main shaft 4. The bearings 5 and 6 are provided in the main part of the frame 3, while a forward bearing 7 is provided in a forward portion 8 of the frame which projects out beyond and overhangs the forward surface 1^x of the support 1 so as to expose the lasting instrumentalities in convenient position for use and so that manipulation of the shoe while being lasted will not be interfered with by contact with the support 1.

Loosely mounted on the rear end of the shaft 4 is a drive pulley 9 which may be coupled, at will, to the shaft by means of a clutch 10. This clutch may be of any conventional type and need not be described in detail, but is furnished with an actuating lever 11 (Fig. 2) which is connected by a rod 12 to a treadle not shown by means of which the operator is enabled to actuate the clutch and thus couple the pulley 9 to the shaft 4. A belt 13 (Fig. 2) embraces a pulley 9 and also a pulley 14 on the shaft of a drive motor 15 mounted within the hollow support 1.

The shaft 4 (Fig. 3) is provided at its forward part with a worm 16 which constantly meshes with a worm wheel 17 fixed to the upper end of a vertical shaft 18 mounted in bearings in the frame member 8 and which is provided with a pinion 19, preferably of the helical tooth type, which constantly meshes with a complementary pinion 20 fixed to the upper end of a vertical shaft 21 also having bearings in the main frame part 8 and which is provided at its lower end with a lasting roll 22, here shown as provided with a helical rib. A complementary lasting roll 23, preferably of somewhat smaller diameter than the roll 22, is fixed to the lower end of the vertical shaft 24 provided at its upper end with a worm wheel 25 which constantly meshes with the worm 16. The shaft 24 is mounted to turn in bearings in a horizontally movable slide member 26 (Figs. 2 and 3) mounted to slide in guideways in the main frame 3 and which is constantly urged rearwardly by means of a spring 27 whereby the forward lasting roll 23 is urged toward the rear roll 22. The slide 26 (Fig. 2) is provided with a lat-

erally projecting pin 28 which is engaged by a forked lever 29 fixed to a shaft 30 to which is fixed a lever arm 31 pivotally connected to a rod 32 extending downwardly to a treadle (not shown) the arrangement being such that when the treadle is depressed the shaft 30 is rocked thereby moving the slide 26 forwardly so as to separate the lasting rolls 23 and 22 to permit ready introduction of the margin of the shoe upper between them.

Immediately below the lower end of the roll 23 there is arranged a rigid work rest and anvil 34 carried by a vertically adjustable bracket 35 supported by the slide member 26. This work rest 34 is designed to engage the surface of the insole of the shoe being lasted, thereby to oppose the upward pull of the lasting rolls and thus insure the proper stretching of the upper material about the last, and also, in this instance, to form a rigid abutment or anvil against which the ends of the fasteners are clenched.

The mechanism as thus far described is in general substantially identical with that disclosed in the patent to Kamborian No. 2,251,285 dated August 5, 1941, and functions in lasting the shoe substantially in the same way as the corresponding parts of the machine of said patent.

The staple forming and driving instrumentalities and the means for actuating them are for the most part supported by or housed within the casing 36 (Figs. 2, 3, 4, 7, 8 and 9) which is secured to the under side of the plate 2. This casing 36 is preferably a rigid hollow casting of generally circular form except that it has a forwardly projecting elongate nose member 37 (Fig. 4) symmetrically disposed with respect to the vertical plane of the axes of the shafts 21 and 24. This nose member (Figs. 7, 8, 9 and 13) comprises spaced parallel guides 37^a and 37^b, respectively, having finished parallel inner surfaces in which reciprocates a head 49^a (hereinafter described) constituting a support for the forming and driving instrumentalities. The casing 36 is provided with a hollow boss 38 (Fig. 4) at its bottom which holds a bearing 39 for a vertical shaft 40 which has a second bearing in the frame member 3, and which is provided at its upper end with a worm wheel 41 (Fig. 3) which is always in mesh with a worm 42 on the shaft 4. Mounted on the shaft 40, within the lower part of the casing 36, is an eccentric 43 (Figs. 8 and 10) having a strap 44. Above this eccentric there is fixed to the shaft a cam disk 45 (Figs. 4 and 9) having a cam groove 46 in its upper surface; a cam groove 47 in its lower surface; and a peripheral cam rib 48.

The eccentric rod 49, Fig. 10, which is secured to the eccentric strap 44, extends forwardly between the guide members 37^a and 37^b and is provided at its forward end with a head 49^a having lateral ribs 50 which slide in guide slots 51 (Fig. 13) in the inner surfaces of the guide members 37^a and 37^b. The head 49^a is preferably furnished with an upwardly sloping beveled forward surface 52 and has a recess in its upper surface for the reception of the staple-forming block 53 (Figs. 11, 13, 14 and 27) which is secured in the slot by rivets 54. This block 53 has a vertically narrow front face 55 having therein a transverse groove 56 of such dimensions as to accommodate (with a snug sliding fit) the wire from which the staples are to be formed. The block 53 is provided with a longitudinal substantially cruciform guide slot 57 in its upper face whose side walls have the parallel guide grooves 58. Within this slot 57 the staple driver 59 (Figs. 19 and 28) is

arranged to slide, this driver having lateral ribs 60 which are received within the slots 58. The forward end (Fig. 28) of the staple-driving head 59 is preferably beveled at top and bottom at 61 and preferably has a groove 62 at its forward end to receive the staple-forming wire.

The rear end of the staple driver 59 is pivotally secured (Fig. 8) by a pin 59^a (Fig. 10) to an actuating slide 63 arranged to reciprocate in guides 64 (Fig. 8) forming a part of the case 36. The slide 63 is constantly urged forwardly by springs 65 secured at their rear ends to brackets 66 attached to the slide, and which at their forward ends are secured to lugs projecting from the members 37^a and 37^b, respectively. At its rear end the slide 63 is provided with a roll 67 (Figs. 4 and 8) which engages the cam groove 47 in the under side of the cam disk 45.

The members 37^a and 38^a (Fig. 8) are provided at their forward ends with parts 37^x and 37^y respectively constituting vertical guides for a vertically reciprocable staple-bending block 68 (Figs. 7, 8, 11 and 13). This block or former (Figs. 11, 16, 22, 23) is provided at its under side with a pair of spaced downwardly directed forming lugs 69 and 70, respectively, the adjacent surfaces of which are spaced apart a distance substantially equal to the diameter of the wire from which the staples are to be formed. A lug 68^a (Figs. 4 and 9) projects from the rear surface of the block or former 68 and is provided with a pivot pin 71 (Fig. 4) which enters a slot in the forward end of a lever 72 pivoted at 73 on a shaft 73^a extending from the member 37^a to the member 37^b. This lever 72 is provided at its rear end with rolls 74 which engage the peripheral rib 48 on the cam disk 45.

Fixed in an opening in the member 37^a (Fig. 13) is a tubular wire guide 75 whose inner or right-hand end is arranged for sliding contact with the left-hand vertical surface of the forming member 53 as the latter advances. This tubular wire guide has a bore 76 which is such as to confine the wire snugly although permitting it to be advanced through the guide and across the path of the staple former 53. Connected to and in alignment with the outer or left-hand end of the tube 75 is a rigid conduit 77 which leads to the wire feeding block 78 (Figs. 5 and 24) mounted on the plate 2 at the left-hand side of the machine. This block 78 (Fig. 24) has a substantially horizontal guide surface 79 on which slides the feed block 82 having a horizontal ledge 82^a upon which the wire 80 rests as it is fed forward. A swinging retaining pawl 81 urged to the right (Fig. 24) by a light-spring 81^a is arranged to engage the wire and to prevent its rearward movement. The feed block 82 carries one or more swinging feed pawls 83 and 84 arranged to engage the wire on the forward movement of the feed block 82 and to advance the wire a predetermined distance for each forward movement of the block 82. The feed block 82 is provided with a tail member 85 provided with a pin 86 (Fig. 5) which is received in a slot in the end of a lever 87 pivoted at 88 in the frame 3, and having a pin 89 at its opposite end which extends through a slot 90 (Figs. 5 and 6) in the plate 2 and which engages the cam groove 46 in the upper surface of the cam disk 45. A bracket 91 (Fig. 24) is secured to the face of the feed block 78 and is furnished at its free end with a guide loop 92 for the wire 80. A tensioning roll 93 (Fig. 5) is mounted on a lever 94 pivoted at 95 in the plate 2, and which is so urged by a spring 95^a as

to maintain the wire under tension. The wire is supplied from a reel 96 mounted on a pivot 97 carried by the plate 2.

The operation of the machine is substantially as follows, it being understood that the motor 15 has been started and that the operator has actuated the treadle so as to cause the clutch 10 to connect the pulley 9 to the shaft 4. The shaft 4 is thus rotating and by means of the worm 16 is rotating the shafts 21 and 24, and by means of the worm 42 is rotating the shaft 40 together with the eccentric 43 and the cam disk 45.

The operator actuates the treadle which moves the slide 26 forwardly, thereby separating the lasting rolls 22 and 23 so as to permit the margin of the upper to be introduced between the rolls. The slide 26 is then released so that the spring 27 moves the roll 23 rearwardly and thus grips the upper material between the rolls. The rolls, with their oppositely pitched helical ribs, immediately exert an upward drawing action upon the marginal material of the upper so as to draw the upper snugly around the last, upward movement of the last being resisted by the support 34. During this updrawing operation the eccentric 43 and the disk 45 are turning thus rapidly reciprocating the head 49 with the forming block 53, and also reciprocating the staple driving head 59 and moving the block 68 up and down in timed relation to the other parts. It will be assumed that the head 49 and the forming block 53 are in the rearward position as shown in Fig. 14. The feed block 82 is actuated by the cam groove 46 of the disk 45 so as to advance the wire 80 and to push its end 80^a (Fig. 14) out from the end of the tube 75 a distance which provides a length 80^b (Fig. 14) sufficient to form a staple. Immediately thereafter, the head 49 and block 53 begin to advance until the groove 56 in the forward end of the block 53 embraces the projecting length 80^b of a wire. Further advance of the head 53 causes the left-hand surface of the head 53 to pass the right-hand end of the tube 75, in sliding contact, thus shearing off the length of wire 80^b which remains in the groove 56, as an embryo staple S (Fig. 15). Immediately thereafter the former 68 is moved downwardly so that the forming lugs 69 and 70 are disposed at opposite sides of the wire at the central part of the length S. Since the former 68 has no forward motion, the central part of the wire is thus held stationary, and as the forming head 53 continues to advance, the wire is sharply bent so as to form the parallel legs S' and S² (Fig. 16) which are disposed within the grooves 58 of the head 53, these legs S' and S² being united by the transverse rear portion to form a U-shaped staple. The former 68 immediately rises, thus releasing the staple to permit its forward movement with the head 53. The head 53 continues to advance with the completed staple in its forward end until the forward end of the member 53 comes into contact (Fig. 26) with the tensioned upper material at a point just above the upper surface of the feather of the insole. The final advance of the head 53 acts to wipe-in the tensioned material over the edge of the insole, and to press it firmly against the insole rib R, the head 53 thus functioning like the reciprocating wiper of the aforementioned Kamborian patent. At this instant the staple driver 59 is advanced relatively to the head 53 (which now remains momentarily stationary in its most advanced position, with the forward staple housed in the cavity in its forward end) the cam driver 75 engaging the closed rear end of the staple by

its surface 62 and thus forcing the staple out of the cavity in the wiper 53 and through the marginal material of the upper and into the substance of the rib R, the rib being supported during the staple-driving action by engagement of its inner surface with the edge of the work rest 34. The driving motion of driver 59 is produced by the springs 65, and is in the nature of a sudden blow, the cam groove 47 having a radial portion 47^a (Fig. 9) which permits the sudden release of the roll 67 and the instantaneous advance of the drivers. If the staple be long enough to extend entirely through the rib, its ends will contact the edge of the support 34 and thus be clenched, the part 34 constituting an anvil for this purpose. As soon as the staple has been driven, the driver head 59 is retracted and the forming head and wiper 53 is likewise retracted ready for the beginning of the next cycle of operations. It may be noted that during the driving operation the legs S' and S² are confined in the slots 58 of head 53 whose end is pressed firmly against the work, so that during driving the staple legs are constrained to advance in parallel lines. Thus the staple may be driven into very hard dense substances without distortion. The operator moves the shoe so that the lasting rolls 22 and 23 progress relatively to the shoe about the periphery of the last bottom, exerting a constant pull on the upper, whose point of application normally shifts by infinitesimal amounts, the lasting operation being a continuus one so long as the operator keeps the shoe in the operating position. The staples are formed and driven one for each revolution of the shaft 40. In the preferred embodiment of the machine, the rate of staple driving is approximately 175 staples per minute, the ratio of rotation of the shaft 40 to that of the roll shaft 24 being approximately four to one. However, it is contemplated that other speeds of staple-forming and driving may be desired for certain types of work, and the invention is not limited to any particular speed except that the speed of driving should be sufficient to insure a proper wiping-in of the upper material by the head 53 as the material is released by the lasting rolls, and to insure its proper anchorage by the fasteners to the rib of the insole.

While one desirable embodiment of the invention has been illustrated by way of example, it is to be understood that the invention is broadly inclusive of any and all modifications falling within the scope of the appended claims, and that while the machine is primarily designed for lasting welt-type shoes, it may, if merely by modification within the scope of the claims, be employed for stressing and inserting fasteners in flexible material other than shoe uppers.

I claim:

1. A lasting machine comprising means for use in applying lasting tension to a shoe upper, said means including opposed elements operative to grip the lasting margin of the upper between them, at least one of said gripping elements being a power-driven rotatable roll, a wiper for in-wiping the tensioned upper, the wiper having therein a chamber for housing a fastener in readiness to be driven, means for reciprocating said wiper into and out of operative engagement with the upper, means for so positioning a length of material that the wiper, as it advances into such operative engagement, forms a fastener from the material in the chamber, and means for ejecting the fastener so-formed from the chamber and driving it into the upper material while the wiper is in such operative engagement.

2. A lasting machine comprising means for use in applying lasting tension to the shoe upper, said means including opposed power-driven rotatable rolls operative to grip the lasting margin of the upper between them, the axes of said rolls being so disposed as to intersect the bottom of the shoe being lasted, a wiper operative to bend the upper material inwardly across the edge of the insole, said wiper having a chamber therein for the reception of a fastener, means for reciprocating said wiper into and out of operative engagement with the upper, means for so positioning a length of material that the wiper, as it advances into such operative engagement, forms a fastener from the material in the chamber, and means for ejecting the fastener so-formed from the chamber and driving it through the upper material into the insole while the wiper is in such operative engagement.
3. A lasting machine comprising means for use in applying lasting tension to the shoe upper, said means including inner and outer opposed gripping elements operative to grip the lasting margin of the shoe between them, the inner one at least of said gripping elements being a power-driven rotatable roll, a reciprocating wiper and means for advancing the wiper thereby to bend the upper material inwardly across the edge of the insole, said wiper having therein a chamber for the reception of a fastener, means for so positioning a length of material that the wiper, as it advances, forms a fastener from the material in the chamber, and means operative to eject the fastener from said chamber and to drive it through the upper material and into the insole while the wiper is in its most advanced position.
4. A machine for uniting two work pieces by means of an inserted fastener, and comprising means for use in applying tension to one of said work pieces, said means including opposed elements operative to grip said work piece between them, at least one of said gripping elements being a power-driven rotatable roll, an anvil constituting an abutment for the other of said work pieces, a reciprocating presser for pressing the tensioned work pieces against the second work piece, said presser having therein a chamber for a fastener, means for advancing the presser to press the tensioned work piece against the second work piece, means for so positioning a length of material that the wiper, as it advances, forms a fastener from the material in the chamber, and means for ejecting the fastener from said chamber and driving it through the tensioned work piece into the second work piece while the presser is in its most advanced position.
5. A machine for uniting two work pieces by means of an inserted fastener, and comprising means for use in applying tension to one of said work pieces, said means including opposed power-driven rotatable rolls operative to grip said work piece between them, an anvil constituting an abutment for the other of said work pieces, a work-engaging presser having a chamber which is open at the work-engaging surface of said presser, means for advancing said presser into contact with the tensioned work piece thereby to force said tensioned work piece against said second work piece, means for so positioning a length of material that the presser, as it advances, forms a fastener from the material in the chamber with the work penetrating point of the fastener directed forwardly and drives it through the tensioned work piece into the second work piece while

the presser is firmly pressed against the tensioned work piece.

6. A machine for uniting two work pieces by means of an inserted fastener, and comprising means for use in applying tension to one of said work pieces, said means including inner and outer opposed elements operative to receive and to compress said work pieces between them, the inner one at least of said elements being a power-driven rotatable roll, an anvil constituting an abutment for the other of said work pieces, a reciprocating presser operative to press the first of said work pieces against the second work piece while the latter is supported by the abutment, the presser having a cavity in its work-engaging end surface for a fastener, means for so positioning a length of material that the presser, as it advances toward the second work piece, forms a fastener in said cavity, means for ejecting the fastener from the cavity and into the work, and means for advancing the presser thereby to force the first work piece into contact with the second work piece while the latter is supported by the abutment and for actuating the ejecting means while the presser is in its most advanced position.

7. A machine for lasting welt-type shoes, said machine being of the kind having a pair of gripping rolls which seize the lasting margin to advance the shoe and progressively tension such margin, a wiper by which such margin as it leaves said rolls is brought into engagement with the outer surface of the insole rib and means for driving a fastener through the wiped lasting margin into the insole rib as the shoe is advanced.

8. A machine for lasting welt-type shoes, said machine being of the kind having a pair of gripping rolls which seize the lasting margin to advance the shoe and progressively tension such margin, a wiper by which such margin as it leaves said rolls is brought into engagement with the outer surface of the insole rib and means for driving a fastener along a path substantially parallel to the insole and through the wiped lasting margin into the insole rib as the shoe is advanced.

9. A machine for lasting welt-type shoes, said machine being of the kind having a pair of gripping rolls which seize the lasting margin to advance the shoe and progressively tension such margin, a wiper by which such margin as it leaves said rolls is brought into engagement with the outer surface of the insole rib and means for driving a fastener along a path substantially perpendicular to the outer surface of the insole rib through the wiped lasting margin into the insole rib as the shoe is advanced.

10. A lasting machine for lasting welt type shoes, comprising means for tensioning an upper about a last, said means including inner and outer opposed gripping elements operative to grip the lasting margin of the shoe upper between them, each of said elements being a power-driven rotatable roll, the axis of at least one of said elements being so arranged as to intersect the bottom of the shoe being lasted, a wiper for wiping the tensioned upper over the feather of the insole and into contact with the insole rib, the wiper having therein a cavity for holding a staple in readiness to be driven, means for moving the wiper into operative position, means for so positioning a length of wire that the wiper, as it is moved into operative position, will form a staple from such wire and dispose it in the cavity and means for driving the staple into the upper and rib while the wiper is in said operative position.

11. A lasting machine for lasting welt type

shoes, comprising means for tensioning an upper about a last, said means including inner and outer opposed elements operative to receive and to compress the lasting margin of the shoe upper between them, the inner at least of said elements being a power-driven rotatable roll, the axis of which intersects the bottom of the shoe being lasted, a wiper having an upper contacting surface provided with a cavity for housing a staple

5 in readiness to be driven, means for advancing the wiper into contact with the tensioned upper thereby to wipe the margin of the upper over the feather of the insole and into engagement with the insole rib, means for so positioning a length 10 of wire that the wiper, as it is advanced, will form a staple from the wire and dispose it in the cavity and means for driving the staple from the cavity through the upper and into the insole rib while the wiper is in its position of maximum advance.

12. A lasting machine for lasting welt type shoes comprising means for tensioning an upper about a last, said means including inner and outer opposed gripping elements operative to grip the lasting margin of the shoe upper between them, each of said elements being a power-driven

rotatable roll, the axis of at least one of said elements being so arranged as to intersect the bottom of the shoe being lasted, a reciprocating wiper having an end surface for engagement with the tensioned upper, said end surface having therein a chamber for housing a staple, means for advancing the wiper to cause its chambered end to engage the tensioned upper material and to push said material over the feather of the insole

35 and into contact with the insole rib, means for so positioning a length of wire that, as the wiper is advanced, its chambered end will engage said wire, form a staple therefrom and dispose it within said chamber in readiness to be driven, and 40 means for ejecting the staple from the chamber and driving it through the upper and into the insole rib while the wiper is in its advanced position.

13. A lasting machine for lasting welt type shoes, said machine comprising means for tensioning an upper about a last, said means including inner and outer opposed elements operative to receive and to compress the lasting margin of the shoe upper between them, the inner at least of said elements being a power-driven rotatable roll, the axis of which intersects the bottom of the shoe being lasted, a reciprocating wiper having an end surface for engagement with the tensioned upper material, said end surface having a chamber therein for housing a staple, means for advancing the wiper to cause its chambered end to

50 engage the tensioned upper material and to push the latter inwardly over the feather of the insole and into contact with the insole rib, means for so positioning a length of wire that, as the wiper is advanced, its chambered end will engage said wire, form a staple therefrom and dispose the staple in the chamber with its points directed outwardly, and driving means engageable with the staple in the chamber to force the staple from the chamber, through the upper material and into the insole rib while the wiper is holding the upper material in contact with the rib.

14. A machine for lasting welt-type shoes, said machine being of the kind which has a pair of oppositely turned work-gripping rolls operative to progress the work and grip the margin of the shoe upper while lasting stress is being applied to the upper, and a presser device movable in a path substantially parallel to the exposed surface 70 of the insole and which is operative to bend the

11

upper material over the feather of the insole and into contact with the outer surface of the insole rib, characterized in having a normally stationary anvil which engages the inner surface of the insole rib and means for advancing a fastener along a path substantially parallel to the exposed surface of the insole and through the upper material and rib into clenching engagement with the anvil while the work is in progress.

15. A machine for lasting welt-type shoes, said machine being of the kind which has a pair of oppositely turned work-gripping rolls operative to progress the work and grip the margin of the shoe upper while lasting stress is being applied to the upper and a presser device movable in a path substantially parallel to the exposed surface of the insole and which is operative to bend the upper material over the feather of the insole and into contact with the outer surface of the insole rib, the advancing end of the presser device being engaged with the marginal material of the upper immediately after the latter is gripped by the rolls, characterized in that the presser has therein a fastener-receiving chamber open at the work-engaging end of the presser, and drive means operative to eject a fastener from said chamber and to drive it through the upper material and rib into clenching engagement with the anvil while the work is in progress.

16. A lasting machine of the kind which includes an upper tensioning wiper, a pair of work-gripping feed rolls operative to grip the margin of the upper material between them and to progress the work relatively to the path of the wiper, means operative to guide the tensioning wiper to move in a path such that it engages the marginal material of the upper between the insole and the point where the work is gripped by the rolls, and means to reciprocate the wiper in said path whereby its engagement with the marginal material tensions the latter and tends to bend it inwardly over the edge of the insole, characterized in that the wiper has therein a guideway for a fastener driver and a chamber in its work-engaging end for a fastener, and in having means for actuating the driver to insert the fastener into the work while the wiper is in its most advanced position and the work is in progress.

17. A lasting machine of the kind which includes an upper tensioning wiper, a pair of work-gripping feed rolls operative to grip the margin of the upper material between them and to progress the work relatively to the path of the wiper, means operative to guide the tensioning wiper to move in a path such that it engages the marginal material of the upper between the insole and the point where the work is gripped by the rolls, and means to reciprocate the wiper in said path whereby its engagement with the marginal material tensions the latter and tends to bend it inwardly over the edge of the insole, characterized in that the wiper has a longitudinal passage, a driver which fits snugly within and slides in said passage, the forward end of the passage constituting a fastener-receiving chamber and being open at the work-engaging face of the wiper, and means for advancing the driver along said passage to drive the fastener into the work while the work is in progress.

18. A lasting machine of the kind which includes an upper tensioning wiper, a pair of work-gripping feed rolls operative to grip the margin of the upper material between them and to progress the work relatively to the path of the wiper, means operative to guide the tensioning wiper to

12

move in a path such that it engages the marginal material of the upper between the insole and the point where the work is gripped by the rolls, and means to reciprocate the wiper in said path whereby its engagement with the marginal material tensions the latter and tends to bend it inwardly over the edge of the insole, characterized in that the wiper has a longitudinal guideway, a driver which fits snugly within and slides in said guideway, the forward end of the guideway constituting a fastener-receiving chamber and being open at the work-engaging face of the wiper, an eccentric for reciprocating the wiper, and a cam and a spring for reciprocating the driver, the eccentric and the cam being so relatively arranged that the driver is actuated to insert the fastener while the wiper is in its most advanced position and the work is in progress.

19. A lasting machine of the kind which includes an upper tensioning wiper, a pair of work-gripping feed rolls operative to grip the margin of the upper material between them and to progress the work relatively to the path of the wiper, means operative to guide the tensioning wiper to move in a path such that it engages the marginal material of the upper between the insole and the point where the work is gripped by the rolls, and means to reciprocate the wiper in said path whereby its engagement with the marginal material tensions the latter and tends to bend it inwardly over the edge of the insole, characterized in that the wiper has a work-engaging end surface provided with a transverse channel, the wiper also having a longitudinal guideway for a driver, said guideway intersecting the channel at the mid-point of the latter, the forward end of the guideway constituting a fastener-receiving chamber, means for advancing a length of wire into said transverse channel, means whereby said length of wire is cut off from the supply, means for forming the wire into a staple while disposing it in said chamber, a driver sliding in said guideway, and means for advancing the driver to eject the staple from said chamber into the work while the wiper is in its most advanced position.

20. A lasting machine comprising a pair of oppositely turning work-gripping rolls operative to grip the margin of the shoe upper while lasting stress is being applied to the upper, a wiper for wiping-in the marginal material of the shoe upper, means for guiding the wiper to move back and forth in a path so located that the work-engaging end of the wiper contacts the marginal material of the upper immediately after the latter has been gripped by the rolls, characterized in that the work-engaging end of the wiper has a transverse channel, the wiper also having a longitudinal guideway for a driver, said guideway intersecting the transverse channel and the forward end of the guideway constituting a fastener-receiving chamber, means for disposing a length of wire in the transverse channel, forming means engageable with the central portion of the wire, means for advancing the wiper relatively to the forming means thereby to bend the opposite end portions of the wire to form a U-shaped staple, while concomitantly disposing said staple in the chamber in the wiper, means for withdrawing the forming device, a driver sliding in said guideway, and means for advancing the driver to eject the staple from said chamber while the wiper is in engagement with the upper material.

21. Shoe lasting apparatus of the kind having upper stretching and in-wiping means, the stretching means being designed and arranged

positively to grip a length of the margin of the upper and after stressing the gripped portion of the margin in a direction away from the last bottom to release the gripped portion while concomitantly gripping an adjacent portion, the in-wiping means comprising a reciprocating wiper so guided and actuated as to engage the stressed portions of the margin of the upper, characterized in that the wiper has a longitudinally extending, transversely cruciform guideway open at the work-engaging end of the wiper, a driver which fits snugly within and slides in the guideway, the forward ends of the transverse arms of the guideway being dimensioned to receive the respective legs of a staple with a close sliding fit, and means for advancing the driver relatively to the shoe upper so as to eject the staple from the wiper and drive it into the work.

22. Shoe lasting apparatus of the kind having upper stretching and in-wiping means, the stretching means being designed and arranged positively to grip a length of the margin of the upper and after stressing the gripped portion of the margin in a direction away from the last bottom to release the gripped portion while concomitantly gripping an adjacent portion, the in-wiping means comprising a reciprocating wiper so guided and actuated as to engage the stressed portions of the margin of the upper, characterized in that the wiper has a longitudinally extending, transversely cruciform guideway and a driver which slides within the guideway, the wiper having a transverse channel in its work-engaging face which intersects the guideway, means for disposing a length of wire in said channel, a former, means to advance the former so as to dispose it transversely of the guideway and across the central portion of said length of wire, the wiper actuating means being designed to advance the wiper relatively to the former thereby to bend the wire to a U-form and to dispose the legs of the staple thus made in the transverse arms of the guideway, means to withdraw the former from the staple, and means to advance the driver along the guideway to drive the staple into the work.

23. Shoe lasting apparatus of the kind having upper stretching and in-wiping means, the stretching means being designed and arranged positively to grip a length of the margin of the upper and after stressing the gripped portion of the margin in a direction away from the last bottom to release the gripped portion while concomitantly gripping an adjacent portion, the in-wiping means comprising a reciprocating wiper so guided and actuated as to engage the stressed portions of the margin of the upper, characterized in that the wiper has a longitudinally extending guideway, a driver sliding in the guideway, the wiper having a transversely elongate channel in its work-engaging end into which the guideway opens, means for disposing a length of wire in said channel, a former device reciprocable perpendicularly to the path of the wiper and into and out of the guideway and means for reciprocating the former, means for advancing the wiper while the former is disposed in engagement with the central part of the wire thereby to bend the length of wire to form a U-shaped staple having its respective legs disposed against the opposite walls of the guideway, and means for actuating the driver, after the former has been withdrawn from the guideway and relatively to the wiper, thereby to eject the staple from the wiper and to force it into the work.

24. Shoe lasting apparatus of the kind having upper stretching and in-wiping means, the stretching means being designed and arranged positively to grip a length of the margin of the upper and after stressing the gripped portion of the margin in a direction away from the last bottom to release the gripped portion while concomitantly gripping an adjacent portion, the in-wiping means comprising a reciprocating wiper so guided and actuated as to engage the stressed portions of the margin of the upper, characterized in that the wiper has a longitudinally extending guideway, a driver sliding in the guideway, the wiper having a transversely elongate channel in its work-engaging end into which the guideway opens, means for disposing a length of wire in said channel, means for retarding the central portion of the length of wire while the wiper is advanced, thereby to bend the wire to form a U-shaped staple with the points of the staple directed forwardly and with its legs disposed in contact with the opposite walls respectively of the guideway, and means for advancing the driver relatively to the wiper to eject the staple from the guideway and to drive it into the work.

25. Shoe lasting apparatus of the kind having upper stretching and in-wiping means, the stretching means being designed and arranged positively to grip a length of the margin of the upper and after stressing the gripped portion of the margin in a direction away from the last bottom to release the gripped portion while concomitantly gripping an adjacent portion, the in-wiping means comprising a reciprocating wiper so guided and actuated as to engage the stressed portions of the margin of the upper, characterized in that the wiper has a longitudinally extending guideway, a driver sliding in the guideway, the wiper having a transversely elongate channel in its work-engaging face into which the guideway opens, means for disposing the length of wire in the channel, a former device having a pair of lugs spaced from front to rear a distance substantially equal to the diameter of the wire, means for guiding said former to move in a path perpendicular to the path of the wiper whereby the lugs of the former may be projected into the guideway so as to engage the central portion of the wire between them, means for advancing the wiper relatively to the former thereby to bend the length of wire to form a U-shaped staple with its points directed forwardly and with its respective legs contacting the opposite walls of the guideway, means for continuing advance of the wiper after withdrawal of the former from the guideway, thereby to press the end of the wiper against the upper material, and means for advancing the driver relatively to the wiper thereby to eject the staple and drive the latter into the work.

26. A lasting machine of the kind having a pair of oppositely turning work-gripping rolls operative to grip the margin of the shoe upper while lasting stress is being applied to the upper, a wiper for wiping-in the marginal material of the upper, means for guiding the wiper to move back and forth in a path so located that the wiper engages the marginal material of the upper substantially as soon as it is stressed and wherein a driven shaft has a worm for driving the rolls, characterized in that said driven shaft has another worm which meshes with a worm wheel mounted on a wiper-actuating shaft, the latter having thereon an eccentric for reciprocating the wiper, said wiper-actuating shaft also carrying

cams for actuating fastener-forming and inserting means.

27. A lasting machine of the kind having a pair of oppositely turning work-gripping rolls operative to grip the margin of the shoe upper while lasting stress is being applied to the upper, a wiper for wiping-in the marginal material of the upper, means for guiding the wiper to move back and forth in a path so located that the wiper engages the stressed marginal material while it is gripped by the rolls and wherein a driven shaft has a worm for driving the rolls characterized in having a former device, movable in a path perpendicular to the path of the wiper, said former device being cooperable with elements of the wiper to form a staple, and a driven shaft having thereon means for actuating the wiper and means for moving the former.

28. A lasting machine of the kind having a pair of oppositely turning work-gripping rolls operative to grip the margin of the shoe upper and progress the work while lasting stress is being applied to the upper, a wiper for wiping-in the marginal material of the upper, means for guiding the wiper to move back and forth in a path so located that the wiper engages the marginal material of the upper immediately after it has been gripped by the rolls and wherein a driven shaft has a worm for driving the rolls and having wire-feeding means operative to deliver wire in predetermined lengths to staple-forming means characterized in having a former which cooperates with elements of the wiper to form a staple and in having a driven shaft carrying means for actuating the wiper, former and wire-feeding means in predetermined timed relation while the work is in progress.

29. Apparatus for lasting welt-type shoes having a pair of oppositely rotating upper gripping rolls so constructed and arranged as positively to grip the margin of the upper at a selected point and to apply stress thereto tending to stretch the upper about the last, the rolls always turning in the same direction to progress the work and being constructed and arranged to exert a component of stress longitudinally of the shoe thereby to cause the point of application of stretching stress to progress continuously from point to point along the edge of the insole, and a reciprocating wiper device operative by engagement with the upper, while tensioned by said rolls, to force the upper inwardly over the feather of the insole and into engagement with the insole rib, characterized in having a stationary clenching anvil arranged to engage the surface of the insole and to constitute an abutment for the inner surface of the insole rib, the wiper having a chamber in its work-engaging end and being movable toward and from the anvil, means for disposing a fastener in the chamber in the end of the wiper, and means for forcing the fastener through the upper material and into the rib and into clenching engagement with the anvil while the work is in progress.

30. Apparatus for lasting welt-type shoes having a pair of oppositely rotating upper gripping rolls so constructed and arranged as positively to grip the margin of the upper at a selected point and to apply stress thereto tending to stretch the upper about the last, the rolls always turning in the same direction to progress the work and being constructed and arranged to exert a component of stress longitudinally of the shoe thereby to cause the point of application of stretching stress to progress continuously from

point to point along the edge of the insole, and a reciprocating wiper device operative by engagement with the upper while tensioning by said rolls, to force the upper inwardly over the feather of the insole and into engagement with the insole rib, characterized in having a normally stationary anvil so located with reference to the rolls as to engage the surface of the insole at a point just inside the insole rib and to hold the insole at such a level that the top edge of the insole rib just clears the lower ends of the rolls, the wiper having a fastener-receiving chamber in its work-engaging end, means for guiding the wiper so that said end moves toward and from the anvil, the wiper engaging the stressed margin of the upper as the upper advances and forcing it against the outer surface of the insole rib, and means for ejecting the fastener from the wiper chamber and into the work while the wiper is so advanced and the work is in progress.

31. Apparatus for lasting welt-type shoes having a pair of oppositely rotating upper gripping rolls so constructed and arranged as positively to grip the margin of the upper at a selected point and to apply stress thereto tending to stretch the upper about the last, the rolls always turning in the same direction and being constructed and arranged to exert a component of stress longitudinally of the shoe thereby to cause the point of application of stretching stress to progress continuously from point to point along the edge of the insole, and a reciprocating wiper device operative by engagement with the upper, while tensioned by said rolls, to force the upper inwardly over the feather of the insole and into engagement with the insole rib characterized in having wire-feeding means comprising a reciprocating carrier and a wire-engaging feed dog mounted on the carrier, staple-forming and driving means, the wiper having a chamber in its work-engaging end for the reception of the formed staple and means for actuating the wire-feeding carrier, staple-forming and driving means and wiper in properly timed relation thereby to drive the staple through the tensioned upper and through the insole rib and into clenching engagement with the anvil while the wiper is in its most advanced position.

32. A machine for lasting welt-type shoes, said machine being of the kind having a pair of upper gripping rolls, means for driving the rolls in opposite directions to progress the work and means resiliently urging one roll bodily toward the other characterized in having an anvil engageable with the surface of the insole at a point just inside the insole rib thereby to space the upper edge of the insole rib from the lower ends of the rolls, a reciprocating presser device operative to bend the upper material inwardly over the feather of the insole and into contact with the outer surface of the insole rib, said presser device having therein a cavity for the reception of a fastener, and means for ejecting the fastener from said cavity while the presser is in engagement with the upper and for driving the fastener through the upper and rib into clenching engagement with the anvil while the work is in progress.

33. A machine for lasting welt-type shoes, comprising means for use in applying lasting tension to the shoe upper, said means including opposed power-driven rotatable rolls operative to receive and to compress the lasting margin of the upper between them, the axes of said rolls being so disposed as to intersect the bottom of the shoe being lasted, a reciprocating wiper whose end surface

17

engages the tensioned upper margin to force the upper inwardly over the feather of the insole and into engagement with the insole rib, a normally stationary anvil adapted to support the inner face of the rib when the wiper brings the upper margin into engagement therewith, means for reciprocating the wiper, means acting, as the wiper is advanced into engagement with the tensioned upper material, to cause the end surface of the wiper to form a staple, and means carried by the wiper and acting, when the wiper has forced the upper into engagement with the rib to drive the staple through the upper and into the insole rib.

34. A machine for lasting welt-type shoes, comprising means for use in applying lasting tension to the shoe upper, said means including inner and outer opposed gripping elements operative to grip the lasting margin of the shoe between them, the inner one at least of said gripping elements being a power-driven rotatable roll, a reciprocating wiper whose end surface engages the tensioned upper margin to force the upper inwardly over the feather of the insole and into engagement with the insole rib, a normally stationary anvil adapted to support the inner face of the rib when the wiper brings the upper margin into engagement therewith, means for reciprocating the
